ELECTRON TUBE HAVING ANNULAR
ENVELOPEClayton E. Murdock, Millbrae, Calif., assignor to
Etel-McCullough, Inc., San Bruno, Calif., a
corporation of California

Application December 26, 1947, Serial No. 794,000

8 Claims. (Cl. 250—27.5)

1

My invention relates to electron tubes, and more particularly to power or transmitting type tubes adapted for operation at the higher frequencies.

The broad object of my invention is to provide a tube structure having the relatively large cathode area and heat dissipation capabilities required for high power operation.

Another object is to provide a tube having an improved electrode terminal arrangement adaptable for use with high frequency linear circuits.

The invention possesses other objects and features of advantage, some of which, with the foregoing, will be set forth in the following description of my invention. It is to be understood that I do not limit myself to this disclosure of species of my invention as I may adopt variant embodiments thereof within the scope of the claims.

Referring to the drawing:

Figure 1 is an axial sectional view of a tube embodying the improvements of my invention; and

Figure 2 is a fragmentary sectional view showing a modified structure with a single grid terminal and an indirectly heated cathode.

In terms of broad inclusion my tube comprises an annular envelope having cylindrical inner and outer side walls, a plurality of ring-shaped electrodes, and ring-shaped electrode terminals on the envelope, the envelope side walls and electrodes and electrode terminals all being concentric with the tube axis. In a triode type of tube having an anode, grid and cathode, the anode preferably forms a part of one side wall and a cathode terminal a part of the other side wall, the grid terminal being preferably located between the side walls at one end of the envelope. My improved tube structure is adapted to employ either a single or double terminal arrangement for the grid, and either a directly or indirectly heated cathode may be used to advantage in the tube.

In greater detail, and referring to Figure 1, a triode type of tube embodying my invention comprises an annular evacuated envelope 2 and ring-shaped electrodes including an anode 3, grid 4 and cathode 6. An envelope of this shape has cylindrical inner and outer side walls, and in my preferred structure the metal anode 3 forms a part of the outer wall. Two ring-shaped cathode terminals 7 and 8 are provided on the envelope and are preferably arranged to form part of the inner wall of the envelope. These terminals are conveniently cylindrical metal sleeves

2

disposed one within the other, the inner terminal 7 of which lies in the circle defined by the inner envelope wall. Two ring-shaped grid terminals 9 and 10 are also preferably provided on the envelope. These are coaxially aligned cylindrical metal sleeves and are located between the side walls at opposite ends of the envelope.

The vacuum-tight envelope is completed by several sections of insulating or vitreous material such as glass. Upper and lower end sections 11 and 12 of annular U-shape complete the outer wall and are sealed along the outer edges to flanges 13 connected to the anode 3. Shields 14 on flanges 13 protect the seals against heat and electron bombardment. The inner edges of glass sections 11 and 12 are sealed to flanges 15 on the grid terminals 9 and 10. Another annular U-shaped section 16 at the upper end of the tube is sealed along one edge to a flange 17 on the upper grid terminal 9 and along another edge to a flange 18 on the cathode terminal 7. A similar but smaller section 19 at the lower end of the tube is sealed along one edge to a flange 21 on the lower grid terminal 10 and along the other edge to a flange 22 on the cathode terminal 8. The cathode terminals are joined by a glass ring 23 sealed to flanges 24 and 25 on the terminals.

This completes the envelope and provides exposed surfaces on the several terminals externally of the envelope. As clearly seen in Figure 1, the envelope side walls, the three electrodes and the various electrode terminals are all coaxial with the envelope axis 27.

The ring-shaped grid 4 lies as a cylinder between cathode 6 and anode 3 and is supported by metal end rings 28 and 30 projecting from the grid terminals 9 and 10 respectively. The grid may be of any suitable openwork structure such as vertical bars extending between the end rings. This preferred double-ended grid terminal arrangement has the advantage of being able to make circuit connections at either or both ends of the tube, and the additional advantage of providing support for both ends of the grid.

The ring-shaped cathode 6 lies as a cylinder inside the grid. In the tube illustrated in Figure 1, a filamentary type of cathode is used, comprising a series of parallel thoriated tungsten wires. These wires are supported at the ends by circular supports 29 projecting radially from mounting rings 31 fastened to the cathode terminals 7 and 8. By this arrangement a multiplicity of filament wires are provided, whereby a large cathode area is presented to the anode of the tube. Such large electron emitter surface is im-

portant in high power tubes. In order to improve the thermal efficiency of the cathode, a cylindrical heat shield 32 is located back of the filaments, which shield is conveniently supported from the mounting ring 31 by a flange 33.

My improved tube has many advantages. The desired large cathode area is provided in a structure embodying fairly short electrodes. This shortness of electrode length is very important, particularly in high frequency tubes. For example, much closer grid-to-cathode spacings can be established and maintained than would be possible if long electrodes were used. Also, the compact coaxial electrodes in combination with the coaxial terminal arrangement provides short, low inductance connections between the electrodes and associated circuits. As already mentioned, the annular tube with its coaxial terminals is well adapted for use with linear circuits.

Another advantage lies in cooling the tube. One of the major problems in high power tubes is the one of heat dissipation. With my improved annular envelope both the inside and outside walls are exposed for removing heat from the electrodes, in fact, the entire central part of the envelope is open to form an air passage. Cooling air may thus be directed along both the inner and outer side walls of the tube. Radial cooling fins 34 retained by a sleeve 35 are preferably provided on the anode 3. This cooler also provides a convenient terminal for making circuit connection to the anode.

Figure 2 shows a modified tube in which only one grid terminal is employed. Here the upper end of the tube is similar to that shown in Figure 1, while the lower end has a single annular U-shaped section 36 sealed along one edge to the anode flange 13 and along the other edge to the cathode terminal flange 22. This view also illustrates the use of an indirectly heated cathode comprising a cathode sleeve 37 connected to a support 38 and heated by filament wires 39 located inside the sleeve, which heater filaments are connected between the support 38 and a second support 41 so that the filaments are connected across the cathode terminals. The cathode sleeve may be coated or treated with any suitable electron emissive material.

I claim:

1. An electron tube comprising an annular envelope having generally cylindrical inner and outer walls, a plurality of ring-shaped electrodes including an anode and grid and cathode, said anode forming part of one of said walls, and ring-shaped terminals on the envelope for the grid and cathode, said walls and electrodes and terminals being concentric with the tube axis.

2. An electron tube comprising an annular envelope having generally cylindrical inner and outer walls, a plurality of ring-shaped electrodes including an anode and grid and cathode, said anode forming part of one of said walls, and ring-shaped terminals on the envelope for the grid and cathode, one of said terminals forming part of the other of said walls, said walls and electrodes and terminals being concentric with the tube axis.

3. An electron tube comprising an annular envelope having generally cylindrical inner and outer walls, a plurality of ring-shaped electrodes including an anode and grid and cathode, said anode forming part of one of said walls, and ring-

shaped terminals on the envelope for the grid and cathode, the cathode terminal forming part of the other of said walls and the grid terminal being located between the walls at one end of the envelope, said walls and electrodes and terminals being concentric with the tube axis.

4. An electron tube comprising an annular envelope having generally cylindrical inner and outer walls, a plurality of ring-shaped electrodes including an anode and grid and cathode, said anode forming part of one of said walls, a ring-shaped terminal on the envelope for the cathode, and a pair of aligned ring-shaped terminals on the envelope for the grid, the cathode terminal forming part of the other of said walls and the grid terminals being located between the walls at opposite ends of the envelope, said walls and electrodes and terminals being concentric with the tube axis.

10 5. An electron tube comprising an annular envelope having generally cylindrical inner and outer walls, a plurality of ring-shaped electrodes including an anode and grid and cathode, said anode forming part of the outer wall, and ring-

15 shaped terminals on the envelope for the cathode and grid, one of said terminals forming part of the inner wall, said walls and electrodes and terminals being concentric with the tube axis.

20 6. An electron tube comprising an annular envelope having generally cylindrical inner and outer walls, a plurality of ring-shaped electrodes including an anode and grid and cathode, said anode forming part of the outer wall, and ring-

25 shaped terminals on the envelope for the cathode and grid, one of said terminals forming part of the inner wall, said walls and electrodes and terminals being concentric with the tube axis.

30 6. An electron tube comprising an annular envelope having generally cylindrical inner and outer walls, a plurality of ring-shaped electrodes including an anode and grid and cathode, said anode forming part of the outer wall, and ring-

35 shaped terminals on the envelope for the cathode and grid, one of said terminals forming part of the inner wall, said walls and electrodes and terminals being concentric with the tube axis.

40 7. An electron tube comprising an annular envelope having generally cylindrical inner and outer walls, a plurality of ring-shaped electrodes including an anode and grid and cathode, said anode forming part of one of said walls, a pair of ring-shaped

45 cathode terminals on the envelope, said cathode terminals forming part of the other of said walls, the cathode comprising a series of parallel filaments, and a pair of spaced supports projecting radially from said terminals and connected to the

50 ends of the filaments, said walls and electrodes and terminals being concentric with the tube axis.

8. An electron tube comprising an annular envelope having generally cylindrical inner and outer walls, a plurality of ring-shaped electrodes including an anode and grid and cathode, said anode forming part of one of said walls, and a cylindrical heat shield interposed between the cathode and the other of said walls, said walls and electrodes and shield being concentric with the tube axis.
